CHARLES MILTON CLEAVLAND, OF WAUSAU, WISCONSIN, ASSIGNOR OF ONE-FOURTH TO
HIRAM DUNFIELD, OF WAUSAU, WISCONSIN.

ELECTRIC RAILWAY SIGNALING SYSTEM.

No. 863,509.

Specification of Letters Patent.

Patented Aug. 13, 1907.

Application filed April 8, 1907. Serial No. 367,087.

To all whom it may concern:

Be it known that I, CHARLES MILTON CLEAVLAND, a citizen of the United States, residing at Wausau, in the county of Marathon and State of Wisconsin, have invented a new and useful Electric Railway Signaling System, of which the following is a specification.

This invention relates to railroad signals, and has for its principal object to provide means whereby approaching trains may be warned when they arrive within a danger zone.

A further object of the invention is to provide an electric railway signaling apparatus in which each train carries an independent source of electrical energy for sending a signal to the opposite train and also a receiving apparatus in the form of a visual alarm which is actuated from the source of energy on the other train.

A still further object of the invention is to provide a novel form of traveling contact of such construction as to readily clear the road bed contact and thus prevent damage in case of accidental displacement.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size and minor details of the structure may be made without departing from the spirit or sacrificing any of the advantages of the invention.

In the accompanying drawings:—Figure 1 is a plan view of an electric railway signaling system constructed and arranged in accordance with the invention. Fig. 2 is a transverse sectional view of the traveling contact and road bed contact in operative position. Fig. 3 is a similar view of the devices moved to inoperative position.

Similar numerals of reference are employed to indicate corresponding parts throughout the several figures of the drawings.

In carrying out the invention, each of the traffic rails 10 and 11 forms one leg of a circuit, there being two separate circuits, one under the control of a train moving in one direction, and the other under the control of a train moving in the opposite direction.

At the center of the road bed or other convenient point is placed a supporting rail 15, having recessed side portions, in which are arranged two continuous conductors 16 and 17 which are insulated from the supporting rail 15, and are housed within the recesses, their vertical faces only being arranged to be engaged by traveling contacts, so that they will be relatively free from snow, dirt, and like obstructions. One of the signaling circuits is formed by the traffic rail 10, and the

continuous conductor 16, and the other circuit is formed by the traffic rail 11 and the continuous conductor 17.

On each train, and preferably carried by the locomotive or tender, is a traveling contact of the construction best shown in Figs. 2 and 3. This contact comprises a block 20 having a pair of outwardly extending flanges 21, and the opposite sides of the lower edge of said block are provided with downwardly extending flanges 22 that form guards which may engage with the opposite sides of the rail 15 in order to prevent lateral displacement. The under surface of this block is provided with a wear-strip 25 having upturned ends which are secured to the ends of the block, the wear strip being readily detachable, so that it may be renewed when occasion requires. Extending from the opposite sides of the block are a number of sets of pivot ears 26 between which are pivoted levers 27, the pivotal connections being insulated in order to prevent electrical contact between the arms and block. The lower end of each arm is recessed for the reception of a stud 28 that is loosely mounted therein, and on the lower end of the stud is mounted a contact roller 29 that is arranged to engage one of the continuous conductors of the third rail. The arm is further provided with a downwardly extending flange 30 that forms a guard for the roller 29. The upper portion of the block is provided with recesses for the reception of a number of vertically movable posts 32, there being one of such posts for each pair of pivoted levers 27, and the post is connected to the levers by means of links 33.

When the traveling contact is lowered, the wear strip 25 will first engage with the top of the third rail and the post 32 will then remain stationary. The levers 27 continue to move down and owing to the links 33, the upper ends of said levers 27 will be spread, while the lower ends thereof which move toward each other and the rails 29 will be moved into engagement with the continuous contacts 16 and 17. If for any reason the traveling contact is raised, the first effect will be to move the levers 27 upward and owing to the links 33, the upper ends of said levers will be moved inward, and their lower ends will be spread, thus freeing the rollers 29 from engagement with the conductors and permitting the removal of the traveling conductor from operative position without damage.

On each of the trains is a source of electrical energy, represented in the present instance by small dynamos 40—41, and each train also carries a visual signal 42—43, and a voltmeter, the voltmeters 44—45 and the signals being connected in multiple in the signaling circuit. Each train further carries a pole changing switch, the pole changers 46—47 being of any ordinary construction.

In the operation of the system as thus far described, when the trains A and B approach each other within signaling distance, the dynamo 40 on train A will be connected by the conductors 10 and 16 with the lamp 43 on train B, and the dynamo of train B will be connected by the conductors 11 and 17 with the lamp 42 of train A.

- The current strength may be arranged to display the signals at any desired distance, but in any case the 10 lamps will glow faintly at first and will gradually increase in brilliancy as the trains near each other. The distance between trains may be gaged by the voltmeters 44 and 45, so that the engineers may determine the proper point for stopping or reversing.
- 15 In order that the engineer may be informed as to the operativeness of the circuit, a lamp 50 is connected in series with each of the dynamos, and, if necessary, a switch may be installed in this circuit although if desired the lamp may be arranged to burn continuously.
- 20 The pole changing switches 46 are utilized when trains are following each other in the same direction in order to shift the circuits.

In order to provide for an automatic stoppage of a train, an electric motor 60 may be installed on each 25 train, said motor being suitably connected through gearing to the reversing lever or the engineer's brake valve or both. This motor is arranged in the normally open circuit 61 with the dynamo, and the switch 62 of said circuit is under the control of an electro magnet 30 63 that is connected by wires 64 in the signaling circuit. When the signaling circuit is energized, the electro-magnet 63 is also energized, and attracts an armature lever 64', which in turn trips the switch 62 and closes the circuit 61, so that the motor 60 will be operated 35 from the dynamo and will automatically actuate the

reversing lever, the engineer's brake lever, or other train controlling element.

I claim:—

1. In apparatus of the class described, a supporting rail having recessed sides, a pair of continuous bare conductors arranged within the recesses and insulated from each other, a traveling contact comprising a block having depending spaced flanges serving as guards to prevent lateral play of said block, a detachable wear shoe carried by the block and arranged for contact with the upper surface of the support, a pair of levers pivoted to the block and insulated therefrom, roller contacts arranged at the lower ends of said levers and adapted to engage the conductors, roller guard flanges depending from the levers, posts carried by the block, and links connecting said posts to the 40 levers at a point above the fulcrums of the latter.

2. In apparatus of the class described, a supporting rail having recessed sides, a pair of continuous bare conductors arranged within the recesses and insulated from each other, a traveling contact comprising a block having spaced 45 depending flanges arranged to engage against the opposite edges of the supporting rail to prevent lateral displacement of the block, a detachable wear shoe carried by the block and arranged for contact with the upper surface of the supporting rail, a pair of levers pivotally connected to 50 the block and insulated therefrom, loose stems mounted in said lever, contact rollers carried by the stems and arranged to engage the conductors, said arms having depending flanges extending beyond the outer faces of the rollers, posts secured to and extending upward from the block, links connecting said posts to the levers at points 55 above the fulcrums of the latter, whereby on upward movement of the levers, the rollers will be swung out of engagement with the conductors before the posts and block are lifted by the links.

In testimony that I claim the foregoing as my own, I have hereto affixed my signature in the presence of two witnesses.

CHARLES MILTON CLEAVLAND.
